[57] CLAIM .

The ornamental design for a printer, as shown and described.

DESCRIPTION

FIG. 1 is a front elevational view of a printer showing our new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a perspective view of a printer showing the front, top and left side thereof.

The bottom of the new design is unornamental.
